PICK-UP MECHANISM

David M. Gilman, Brookline, Mass. (% Graphic Equipment Co., 22 Simmons St., Boston 20, Mass.)
Filed Jan. 12, 1960, Ser. No. 1,974
7 Claims. (Cl. 271—27)

The present invention relates to a take-off mechanism adapted to remove individual sheets from a press. More particularly the present invention relates to a device for successive removal of sheets of paper or the like from a press at selected uniform time intervals and in a continuous fashion.

This invention has particular utility in removing sheets in continuous and successive fashion from a printing or silk screen processing machine wherein it is important to be able to synchronize the removal of the sheets with the operation of the printing or silk screen process machine.

The present invention is designed to remove successive sheets of material from a press and redeposit them on a conveyor, dryer or other apparatus in a precisely oriented fashion at uniform time intervals which intervals if desired, may be varied. A further object of this invention is to provide a feed mechanism for feeding successive sheets of material in which the elements of the mechanism engaging the sheet are compact and capable of being inserted and quickly removed from confined or restricted spaces on the press.

It is also an object of the present invention to provide a take-off mechanism of simple and inexpensive construction which is efficient, reliable, and unlikely to require repair or attention.

These and other objects and advantages of the present invention will be more clearly understood when considered in conjunction with the accompanying drawings in which:

FIG. 1 is a perspective view of the invention with portions shown broken-away for clarity,

FIG. 2 is a detail of a valve mechanism,

FIG. 3 is a cross section of the valve mechanism of FIG. 2 taken along the line 3—3 of FIG. 2,

FIG. 4 is a side elevational view of the invention with the pick-up arms in their forward or pick-up position.

FIG. 5 is a fragmentary detail of the pick-up arm and associated mechanism,

FIG. 6 is a perspective detail of the locking mechanism whereby the operating drive is disassociated from the press,

FIGS. 7, 8 and 9 are plan views of the locking mechanism in various positions of operation, and,

FIGS. 10 and 11 are perspective fragmentary details of the invention.

In FIGS. 1 and 4 there is illustrated a supporting frame 1 preferably formed of angle members. The frame 1 includes parallel longitudinal braces 2 and 4 to which is secured the parallel vertical legs 6 and 8. The braces 2 and 4 are rigidly interconnected by a series of cross braces 10, 12 and 14. The frame is further supported and rigidified by a pair of side braces 16 and 18 on either side. Other supporting members may be used as desired. A working surface or table 20 (FIG. 4) is rigidly secured by means of a transverse angle member 21 at the upper ends of the legs 6 and 8. This table 20 is the printing table on which the impression of the sheet material may take place. The legs 6 and 8, for purposes of this specification shall be defined as at the forward end of the device and the cross brace 12 at the rear end.

A pick-up mechanism 25 best illustrated in FIGS. 1, 4 and particularly FIG. 5 is operatively supported by the supporting frame 1. In this pick-up mechanism a sup-

2

porting arm 26 is rigidly secured at its lower end to the shaft 27 which in turn is pivotally secured in the brackets 28 (FIGS. 1 and 4). The brackets 28 are in turn secured to the longitudinal braces 2 and 4 at the rear end thereof. A clamp arm 29 is pivotally secured at the upper end of the support arm 26 with the clamp arm 29 extending normally therefrom as illustrated in FIG. 10. The support arm 26 is preferably pivotally secured to the shaft 27 at the left side thereof as viewed in FIG. 1. As viewed in FIG. 1, clamp arm 29 extends to the left from the support arm 26, so that it projects beyond the side longitudinal brace 2 thereby for purposes of clearance during the operation of the device. The clamp arm 29 projects through the upper end of the support arm 26 to which it is pivotally secured and has rigidly secured to one end the lever 30. This lever 30, which on rotation will cause a corresponding rotation of the clamp arm 29, is in turn pivotally interlinked with the guide arm 31. The guide arm 31 is a tubular shaft closed at its ends extending substantially the length of the support arm 26. At its lower end it is pivotally interlinked with the L-shaped lever 33 having vertical leg 34 and horizontal leg 35. The upper end of the leg 34 is pivotally secured by suitable means to the lower end of the guide arm 31, while the outer end of leg 35 is pivotally secured to the longitudinal brace 2 through a block 37 (FIG. 1). Rigidly secured to the leg 35 close to the block 37 and immediately in front of the support arm 26 is the engaging member 40. This engaging member 40 is adapted to be moved forwardly as the support arm 26 moves forwardly and engages it. Secured to the clamp arm 29 and extending transversely thereto are two or more rigid air tubes 46 having suction cups 41 at their free ends. These rigid tubes may be secured in a manner as illustrated in FIG. 11 by a bolt and clamp mechanism 51 and 52 wherein the bolt 51 projects through the clamp 52 securing the tube 46 to the arm 29. The other ends of the rigid air tubes 46 are connected to the flexible air tubes 55, 56 in turn secured to and interconnected with the interior of the tubular guide arm 31. This guide arm 31 which forms a continuous nonleaking air passage is connected through a flexible tube 56 to a valve mechanism generally designated at 59. On movement of the engaging member 40, the L-shaped lever will pivot (as viewed in FIG. 5) in a clockwise direction, to the position shown in dotted outline, against the tension of spring 49 thereby causing the lever 30 to move about its axis in a clockwise direction (as viewed in FIG. 5). This in turn causes a lowering of the cups 41 with positive force as the support arm 26 moves to its forwardmost position. This downward movement of the cups 41 causes a positive engagement with the upper surface of the table 20 or papers placed upon it. The helical spring 49 interconnects the upper portion of leg 34 with a tongue 45 rigidly connected to and projecting inwardly from the longitudinal brace 2, thereby tensioning the L-shaped leg 33 in a counterclockwise direction as viewed in FIG. 5.

The valve mechanism 59 (FIGS. 2 and 3) is designed to cause a suction in the cups 41 as the support arm 26 moves from a rear to a forward position. The vacuum is maintained on the cups 41 when the support arm has reached its forward position and the sheet material is picked up and carried by cups 41 from the table 20. As the pick-up mechanism 25 moves toward its rearmost position, the vacuum is released and the sheets fall from the cups 41. This valve mechanism 59 is supported on a plate or other suitable means 60 and provides a housing 61 with a pair of transverse passages 63 and 64 (FIG. 3). Inner end of passage 63 is connected to air tube 56, while inner end of passage 64 is connected to a suitable vacuum pump (not shown) through a flexible air tube 65.

The other ends of the passages 63 and 64 open onto the same side of the housing 61 and are operatively connected or disconnected by pivotal movement of the T-shaped valve control arm 67. This valve control arm 67 has a main stem 68 with a recess 69 (FIG. 3) adapted to operatively interconnect the open ends of the passages 63 and 64. This stem is pivotally mounted at its lower end (not shown) to permit movement of the stem 68 from the position shown in FIG. 3 toward the left and back again. In the position illustrated in FIG. 3 the two passages 63 and 64 are interconnected permitting a vacuum pump to draw air through the two passages and consequently through the cups 41, thereby causing a suction or pick-up action at the cups 41. As the stem 68 is moved toward the left or rearwardly, the passage 63 is opened thereby cutting off the vacuum on the cups 41. The support arm 26 is provided with a pin 70 projecting outwardly and adapted to operatively interengage the cross member 71 rigidly secured to the stem 68. This cross member 71 has a centrally located depression 76 bordered by a pair of high spots 74 and 75 which taper outwardly in end sections having end surfaces 72 and 73. Since the axis of the stem 68 is positioned above the axis about which pin 70 rotates, there is an intermittent engagement and disengagement of the pin 70 with the cross member 71. As the support arm 26 moves forward from its rear-most position, the pin 70 rides over the surface 72 and contacts high point 75 causing stem 68 to move forward. This positions the stem 68 in the position as illustrated in FIG. 3, thereby causing a constant vacuum at the cups 41. As the stem 70 moves continuously forward, the vacuum is maintained. This vacuum is maintained while the cups 41 move to their foremost position and start back. The passage 63 opens and the vacuum on the cups is released on the rearward stroke of the support arms when pin 70 rides over the surface 73 and contacts high point 74 thereby releasing sheets of paper which had previously been held by the cups 41. The support arm 26 is now ready for the reset cycle.

The pick-up mechanism 25 is cyclically actuated by a drive mechanism powered by a motor not shown through gear box 75 (FIG. 4). The gear box is connected through suitable coupling 76 to the shaft of a cam 77. A follower arm 78 is pivotally mounted at one end on the supporting shaft 79. The supporting shaft 79 is in turn suitably secured to the frame in journals. The follower arm 78 has a roller 80 adapted to follow the cam and thereby cause the follower arm 78 to rise and drop with the cam 77. The free end of the arm 78 is interconnected to the T-shaped lever 81 through a link 82. The link 82 is pivotally interengaged at its ends, with one end connected to the arm 78 and the other to one end of the cross member of the T-shaped lever 81. This T-shaped lever 81 is inverted and is secured to a shaft 85 extending transverse to the frame 1. Shaft 85 is suitably journaled for rotation in brackets 86. The T-shaped lever is rigidly connected to this shaft at the other end 87 of the cross member. The upper end of stem 88 pivotally engages one end of the elongated lever 89 in turn secured at its other end to the arm 26 preferably between the center of arm 26 and the lower end of arm 26. A helical spring 90 has one end connected to the arm 26 above the lever 89 and the other connected to the leg 6 of the frame 1 thereby tensioning the arm 26 forwardly.

The take-off mechanism may be operatively disengaged from the press by means of a locking device 90a which disengages the follower arm 78 from the cam 77. This locking device 90a is illustrated in FIGS. 6 to 9. The locking device 90a comprises a plate 91 through which is journaled a pin 92. A suitable pull rod (not shown) having an engaging element at one end engages pin 110. Longitudinal movement of this rod pivots arm 93 about pin 92. This lever arm 93 pivotally supports the hook arm 94 which depends from the upper end of lever arm 93 and terminates in a hook 95. A pair of stops 96 and

97 spaced one above the other are secured to the plate 91 in a position to engage the hook arm 94. An adjustable stop 98 is secured above stop 96 at a position more remote from the arm 94. This stop is provided with a spring stop 99. This stop is adapted to engage the upper end of lever arm 93. A flange 100 projects downwardly from the side edge of plate 91 in a plane normal to the plate 91. The hook is adapted to engage a pin 101 (FIG. 7) projecting normally from the free end of the follower arm 78. This hook 95 is normally free of follower arm 78. However, when it is desirable to disengage the pick-up mechanism from the press and when the follower arm has reached its uppermost position, the lever 93 is moved counterclockwise and then clockwise in a sequence successively illustrated in FIGS. 7, 8 and 9. In this sequence the hook arm 94, on counterclockwise rotation of the arm, 93 first engages stop 96. This causes the hook arm 94 to pivot about the stop 96 and cause the hook 95 to engage the pin 101. On subsequent clockwise movement, the pin 101 is lifted upwardly against the lower edge of flange 100 as illustrated in FIG. 9 thereby disengaging the roller 80 from cam 77.

What is claimed is:

1. A device adapted to individually remove sheets from a table comprising a table, a vacuum operated pick-up system having suction cup means, a lever system adapted to move said suction cup means to and from the upper surface of said table and to pivot said suction cup means toward and away from said upper surface, said lever system including an elongated guide arm and elongated support arm, means pivotally supporting said arms below the level of said table, with the upper ends of said arms extending upwardly above said table, said means supporting said guide arm adapted to move said guide arm lengthwise, a lever pivotally interconnecting the upper ends of said arms, means securing said suction cup means to said lever for movement therewith, said suction cup means positioned to contact said table surface on pivotal movement of said arms toward said table, said means supporting said guide arm for lengthwise movement having a portion interengaged with said support arms whereby pivotal movement of said support arm will cause said means supporting said guide arm to move said guide arm lengthwise, means for moving said arms toward and away from said table, and vacuum means for actuating said vacuum pickup system whereby said vacuum is applied to said suction cup means as said suction cup means move from said table.

2. A device as set forth in claim 1 wherein said means supporting said guide arm includes a lower lever pivotally interengaged at one end with and supporting said guide arm, said lower lever having a projecting member integral therewith with said projecting member positioned between said support arm and said table and closely adjacent said support arm, whereby movement of said support arm toward said table will engage said projecting member and cause said lower lever to pivot upwardly thereby moving said guide arm relative to said support arm.

3. A device as set forth in claim 1 wherein said vacuum means includes air passages interconnecting said suction cup means and an air valve, said air valve having ports connected to said air passages and a port adapted to be connected to a vacuum source, means for selectively interconnecting and individually opening said parts, and means operatively interengaging said last mentioned means and said lever system whereby said ports will be selectively interconnected and opened over selected portions of the movement of said arms.

4. A device as set forth in claim 1 wherein said means for moving said arms comprises a cam and lever linkage system interengaging said cam and support arm for movement of said support arm from said table and a spring means for movement of said arm toward said table.

5. A device for cyclical removal of successive sheets 75 from a printing press comprising a supporting frame, a

pick-up mechanism including a support arm pivotally mounted at one end to said supporting frame, a clamp arm pivotally supported at the upper end of said support arm and extending normally therefrom, an elongated guide arm extending generally lengthwise of said support arm, means pivotally interlinking the upper end of said guide arm to said clamp arm for axially rotating said clamp arm, an L-shaped lever pivotally secured at one end to said supporting frame with the other end pivotally interlinked with the lower end of said guide arm, an engaging member fixed to said L-shaped lever and adapted to be moveably engaged by and on pivotal movement of said support arm whereby said L-shaped lever will be pivoted, said guide arm moves generally lengthwise and said clamp arm thereby axially rotated on movement of said support arm, spring means tensioning said L-shaped lever toward a preselected position, a rigid air tube having a suction cup pick-up element at one end extending normal to and fixed to said clamp arm whereby said suction cup will describe an arc on rotation of said clamp arm, means for applying a vacuum through said suction cup including a vacuum pump, an air tube interconnected between said rigid air tube and a valve mechanism, said valve mechanism adapted to maintain said vacuum on said suction cup as said support arm pivots 25 from a forward position to a rearward position, and

means for pivoting said support arm in a cyclical movement to and from said forward and rear positions.

6. A device as set forth in claim 4 wherein said lever linkage system includes a follower arm adapted to contact and follow said cam and means including a hook arm adapted to engage said follower arm and disengage it from contact with said cam for operatively disengaging said device.

7. A device as set forth in claim 6 wherein said means including a hook arm includes pivoting means supporting said hook arm and a leverage system operatively engaging said hook arm for pivotal movement about said pivoting means whereby said hook arm may be selectively engaged or disengaged with said follower arm.
